UNITED STATES PATENT OFFICE.

ELTON F. MAYERS, OF NEW YORK, N. Y.

ENGINE-STARTER.

1,299,370.

Specification of Letters Patent.

Patented Apr. 1, 1919.

Application filed August 17, 1917. Serial No. 186,801.

To all whom it may concern:

Be it known that I, ELTON F. MAYERS, a citizen of the United States, residing at New York City, in the county of New York and 5 State of New York, have invented new and useful Improvements in Engine-Starters, of which the following is a specification.

This invention relates to engine starters of the compressed air type, in which air under 10 pressure is delivered to the engine cylinders to act on the pistons and impart working strokes thereto until the engine begins its own cycle of operation as an explosive engine.

15 One of the principal objects of the present invention is to provide visual indicating means which will inform the operator as to which of the engine pistons are in position to be acted upon by the compressed air to start the engine shaft turning in the proper 20 direction, therefore avoiding the chance of starting the engine in the wrong direction.

A further object of the invention is to 25 control the air connections leading to the cylinders by means of a manually operable lever with the aid of which the compressed air may be delivered first to one group of cylinders and then to another group.

With the above and other objects in view, 30 the invention consists in the novel construction, combination and arrangement of parts, herein described, illustrated and claimed.

In the accompanying drawings:—

Figure 1 is a side elevation of an engine 35 and part of a motor vehicle in which the engine is mounted, showing the air connections.

Fig. 2 is a plan view of the same.

Fig. 3 is a view in elevation of the dash or 40 instrument board of the vehicle, showing the arrangement of valves and valve controlling lever.

Fig. 4 is an enlarged fragmentary sectional view showing the valves and their 45 controlling means.

In carrying out the present invention, I employ a compressed air tank 1 which may be of any size and located at any convenient point in the vehicle as for example under 50 the floor. 2 represents an air compressor driven by an electric motor 3 connected with the source of electrical energy carried by the vehicle. From the air compressor 2, a compressed air pipe 4 leads to the tank 1 and 55 has incorporated therein a check valve 5

which prevents return flow of the compressed air from the tank to the air compressor. 6 represents an air pressure gage connected by a pipe or tube 7 with the tank 1, said pressure gage being conveniently arranged on the dash or instrument board 8 of the vehicle.

A compressed air delivery pipe 9 leads from the tank 1 to the dash 8 at the rear side thereof where it is bifurcated to provide branch connections 10 and 11 one of which leads to one group of cylinders *a* and *c*, being provided with branches 12 and 13 for that purpose. The other branch connection 11 leads to another group of cylinders *b* and *d* and provided with branches 14 and 15 for that purpose. This provides for conducting air under pressure to all of the cylinders of the engine. Located in the branches 10 and 11 are spring closed valves 70 16 and 17 having the stems thereof extended toward each other. Arranged between the adjacent ends of the valve stems is a lever 18 fulcrumed at 19 and adapted when moved to the left to unseat the valve 16 and 75 17 when moved to the right to unseat the valve 16 and 17. By rocking the lever 18 rapidly in opposite directions, air is admitted first to one group of cylinders and then to the other 80 group.

In order that the operator may ascertain 85 which set of pistons is at or near the upper limit of movement thereof, I provide visual indicating means, as follows. On the crank shaft 20 of the engine I place eccentrics 21 at 180° from each other. Around the eccentrics are straps 22 and extending upwardly from said straps are indicating members 23 such as rods, suitable guiding means being provided for said rods. The upper extremities of the rods or indicating members 23 may be observed through openings 24 in the dash or instrument board 8, the openings 24 being preferably glazed. 90 When one group of pistons is at or near the top limit of movement thereof, the corresponding indicating member 23 will also be at or near the top of its movement while the other indicating member 23 will be at or near the lower limit of its movement. 95 The openings 24 are arranged approximately over the respective valves 16 and 17 so that the operator pushes the lever 18 toward that indicating member 23 which is located at the highest point. This unseats 100 110

the respective valve and admits air to the corresponding cylinders driving the pistons downwardly and turning the engine shaft 20 over. As the upper extremity of said indicating member reaches the lower limit of its movement, the operator quickly rocks the lever 18 in the opposite direction thereby cutting off further flow of compressed air to that group of cylinders and admitting air to 10 the other group of cylinders. This may be repeated until the engine takes up its own cycle of operation.

The mechanism hereinabove described is simple and practical in operation and may 15 be easily installed in conjunction with the internal combustion engine of a motor vehicle. 25 designates an electric switch which controls the starting and stopping of the electric motor 3.

20 I claim:

1. The combination with an internal combustion engine embodying a plurality of cylinders and pistons, said pistons being mounted for movement in groups so that 25 one group moves in one direction while another group is concurrently moving in the opposite direction, of a compressed air tank, an air compressor for supplying said tank, a compressed air delivery pipe leading from 30 said tank and having a plurality of branches which connect with the cylinders of the engine, a spring seated valve in each of said branches, and a manually operable lever arranged between said valves and adapted to 35 open said valves alternately to admit compressed air first to one group of cylinders and then to another group.

2. The combination with an internal combustion engine embodying a plurality of cylinders and pistons, said pistons being 40 mounted for movement in groups so that one group moves in one direction while another group is concurrently moving in the opposite direction, of a compressed air tank, a compressed air delivery pipe leading 45 from said tank and having a plurality of branches which connect with the cylinders of the engine, valve mechanism adapted to alternately admit compressed air first to one group of cylinders and then to another group, and a plurality of vertically 50 movable indicators actuated by the crank shaft of the engine and serving to indicate when one group of pistons is up and the other group down.

3. The combination with an internal combustion engine embodying a plurality of cylinders and pistons, said pistons being mounted for movement in groups so that 55 one group moves in one direction while another group is concurrently moving in the opposite direction, of a compressed air supply in communication with said cylinders, valve mechanism adapted to alternately admit compressed air first to one group of 60 cylinders and then to another group, a plurality of vertically movable indicators actuated by the crank shaft of the engine and serving to indicate when one group of pistons is up and the other group down, and 65 glazed observation openings through which portions of said indicators are visible.

In testimony whereof I affix my signature.
EETON F. MAYERS.
